Patented May 18, 1915.

UNITED STATES PATENT OFFICE.

BERTON I. RIKE, OF DAYTON, OHIO, ASSIGNOR TO THE GERMLESS PAPER CUP COMPANY, OF DAYTON, OHIO, A CORPORATION OF OHIO.

HOLDER FOR FOLDING PAPER VESSELS.

1,139,579.

Specification of Letters Patent. Patented May 18, 1915.

Application filed February 29, 1912. Serial No. 680,733.

To all whom it may concern:

Be it known that I, BERTON I. RIKE, a citizen of the United States, residing at Dayton, in the county of Montgomery and State of 5 Ohio, have invented certain new and useful Improvements in Holders for Folding Paper Vessels, of which the following is a specification.

My invention relates to improvements in 10 holders for folding paper vessels, and it relates more particularly to a holder for what are known as sanitary paper cups, and is especially adapted for use at such places as 15 soda water fountains and establishments where soft drinks are served.

The object of my invention is to provide a 20 holder in which a sanitary cup may be readily inserted and removed, and one which will be simple in construction and effective in use.

In the accompanying drawings,—Figure 1 is a perspective view of a holder embodying the invention. Fig. 2 is a perspective view of a portion of one type of a sanitary 25 paper cup adapted for use in connection with the holder. Fig. 3 is a detail of a portion of the cup and also of one of the holding devices; the holding device being shown partly in dotted lines. Fig. 4 is a side view 30 partly in section and partly broken away, of the holder and cup in position therein.

Like parts are represented by similar characters of reference in the several views.

In the said drawings, 1 represents the 35 main body of the holder, which is in the nature of a cup-shaped cylindrical shell, open at the top and bottom, and being provided with a suitable base portion 1^a and handle 2. Secured to the upper portion of the main 40 body portion 1, are two upwardly projecting holding devices, arranged diametrically opposite each other. Each of these holding devices consists of a plate 3, which is secured to the body 1 by riveting or otherwise, from 45 which plate 3, extend arms 4, the upper end of each of said arms being bent over to form a hook-shaped portion 5; the respective arms of each holding device, being preferably projected at an angle in opposite directions, 50 so that the hook-shaped portions thereof will be separated a suitable distance to provide for more effectively holding the cup.

The cup which is preferably used in connection with this holder is usually formed 55 of a cone shape and is represented by the

reference character 6. The cup which is shown in the drawings is one in which the adjacent edges are cemented together, but the holder is equally adapted for holding cups which are simply folded together, such as the cup illustrated in the application Serial No. 680735 of Berton I. Rike and John R. Klin, filed of even date herewith, as well as other forms of folded cups. In practical use, these paper cups are folded flat for shipping purposes and when sprung out to the position shown in the drawings, have more or less elasticity, which tends to throw them back to a folded position. In applying the cup to the holder, it is forced down into the casing 1, with the folded edges of the cup in contact with the rim of the casing, which tends to force the cup out to a true conical form, until the upper edge thereof engages under the hook-shaped portions of the holding devices, whereupon the elasticity of the cup will effectively hold it in position.

It will be seen by this construction that the holder forms no part of the cup and that the upper part of the cup projects a considerable distance above the upper edge of the holder, so that the lips of the user never come in contact with the holder itself. It will also be seen that after use, the cup may be quickly and easily removed and a new cup inserted in the holder, and that as the cup itself forms the entire receptacle for the drink, it is unnecessary to cleanse the holder after each individual use.

While the preferable manner of packing and shipping these cups is by folding them flat and springing them out to a conical-shaped position, yet it will be seen that this holder will also be adapted for use with cups which are not folded but which are nested together, providing the cup is of sufficient size to fit between the hoop-shaped portions of the holding devices; that is, so that when the cup is forced down between the holding devices, it will spring in slightly between the hoop-shaped portions and then spring back again into position beneath the hooks.

Having thus described my invention, I claim:

In a holder for folded paper vessels, an inclosing frame, a handle projecting from said frame, a pair of rigid projections on said frame arranged diametrically opposite

each other and projecting above said frame, one of said projections being arranged coincident with said handle, and each of said projections having a bifurcated hook-shaped upper end, the arrangement of said projections being such that they will engage the rim of said vessel and hold the same in position in said holder by the elasticity of said vessel, leaving substantially half of the rim

of said vessel on each side of said handle 10 unobstructed for the lips of the user.

In testimony whereof, I have hereunto set my hand this 22 day of February 1912.

BERTON I. RIKE.
